UNITED STATES PATENT OFFICE.

LOU L. DEIDRICK, OF CANTON, OHIO.

DESIGN FOR A GARMENT-FASTENING HOOK.

SPECIFICATION forming part of Design No. 32,144, dated January 23, 1900.

Application filed December 16, 1899. Serial No. 740,615. Term of patent 7 years.

To all whom it may concern:

Be it known that I, LOU L. DEIDRICK, a citizen of the United States, residing at Canton, in the county of Stark and State of Ohio, have invented and produced a certain new and original Design for a Garment-Fastening Hook; and I do declare the following to be a full, clear, and exact description of the invention, such as will enable others skilled in the art to which it appertains to make and use the same.

The invention relates to a new and original design for a garment-fastening hook; and it consists of a design of the shape and configuration shown in the accompanying drawing, in which I have illustrated my invention in perspective.

The leading feature of the design comprises the U-shaped rod 1, curved inwardly interme-

diate its ends and outwardly at its lower end, 20 as shown at 2. The upper ends are curved rearwardly, as shown at 3, thence extend vertically downwardly to form parallel members 4, thence laterally toward each other, as shown at 5, thence upwardly and parallel with each 25 other, as shown at 6, thence curved inwardly, as shown at 7, and finally outwardly.

What I claim is—

The design for a garment-fastening hook, substantially as herein shown and described. 30

In testimony whereof I have hereunto set my hand in presence of two subscribing witnesses.

LOU L. DEIDRICK.

Witnesses:

ALICE SECRIST,
JAMES C. DEIDRICK.
